J. MARSDEN

FLY EXIT SCREEN

Filed Jan. 16, 1928

INVENTOR.

Jeremiah Marsden.

BY

Geo. P. Kimmel. ATTORNEY.

UNITED STATES PATENT OFFICE.

JEREMIAH MARSDEN, OF BELLEVUE, IDAHO.

FLY-EXIT SCREEN.

Application filed January 16, 1928. Serial No. 247,117.

- This invention pertains to a window or door screen attachment, particularly to fly exit devices for window or door screens, and constitutes an improvement on the device 5 disclosed in Patent No. 1,441,104 issued to applicant on January 2, 1923.
- An object of this invention is the provision of a device of this character, whereby the same, when properly secured on a window or door screen, will attract flies thereto and provide means for enabling said flies to pass to the opposite side of the screen with slight probability of returning therethrough.
- Another object of the invention is the provision of a device of this character wherein the structure is novel in form, portable, and easily attached or detached to a door or window screen in any desirable position.
- A further object of the invention is the provision of a device of this character which embodies means for encouraging the egress and discouraging the ingress of flies, which is simple in construction, efficient in operation and which may be manufactured at low cost.
- These and other objects of the invention will be apparent from a study of the following detailed description taken in connection with the accompanying drawings wherein:
- Figure 1 is a perspective view of the invention.
- Figure 2 is a vertical longitudinal sectional view taken centrally through the device.
- Figure 3 is a detail elevation of the exit spout of the device showing a portion of the supporting frame therefor in dotted lines.
- Figure 4 is a fragmentary horizontal section showing one of the sides of the device provided with an opening and a closure plug therein.
- The improved device comprises an inverted substantially V-shaped frame 1 of suitable material such as metal or wood and composed of upwardly converging side strips 2 and 3, said side strips being secured together at their upper ends in any suitable manner such as by use of brads 4, Figure 2. Positioned between and secured to strips 2 and 3 at a point near the lower ends thereof is a cross slat 5 of less width than said side strips, said cross slat 5 being provided with a channel 6 for the purpose of receiving a suitable lure such as bait 7. The cross slat 5 is also provided with a beveled outer edge as at 6'.
- Secured to the edges of strips 2 and 3 of the frame 1 are inner and outer reticulated wire mesh fabric sections 8 and 9, the outer section 9 extending from a point near the apex of frame 1 to a point remote from the lower end thereof so that the lower edge of section 9 is in a plane with the horizontal upper face of slat 5. The inner section of fabric 8 extends from the apex of frame 1 to a point flush with the lower end thereof. These wire mesh sections 8 and 9, when secured to frame 1 together with cross slat 5 constitute an enclosure 10 into which flies, lured by bait 7, enter through an opening near the lower end thereof formed by narrow cross slat 5 and the lower edge of fabric 75 section 9.
- The side strip 2 is provided, at a point above the channel 6 in slat 5, with an opening 11, normally closed by a plug 12. Upon removal of plug 12 access may be had to 80 the interior of enclosure 10, thus permitting the introduction of bait into the channel 6 of cross slat 5. Closure plug 12 prevents the escape through opening 11, of any flies that may have entered enclosure 10.
- Mounted on one side of frame 1 at a point near the apex thereof is an exit tube or spout 13, preferably of metal, said exit tube consisting of a tapering body portion extending outwardly and upwardly from the frame, being secured thereto by means of integral ears or flanges 14 formed on one end of said tube. The tube 13 opens into enclosure 10 at its lower end for a purpose to be presently stated.
- Secured to the other side of frame 1 and extending from the apex thereof to a point remote from the upper face of cross slat 5 is a shade member 15 of suitable opaque material, the function of which is to render dark 95 that side of the enclosure opposite the entrance to the exit spout 13.
- The frame 1 is provided, on the side upon which the exit spout is mounted, with a plurality of outwardly and downwardly extending supporting prongs 16, adapted to engage with the wire mesh of a window or door screen.
- The operation of the invention is as follows:
- An opening of sufficient size is formed in the window or door screen to which the de-

vice is to be attached and the spout 13 is projected therethrough. The supporting prongs are passed through the mesh of the screen, thus securing the device to said screen. When in this position, flies, alighting on the screen, will be attracted by bait 7 and enter enclosure 10 through the opening formed in the lower end of the device. Upon entering the enclosure 10 the flies, will 10 be directed toward exit spout 13 by reason of the converging walls 2 and 3 of frame 1. Shade element 15 will cause the flies to be attracted to said exit spout by reason of the light entering therethrough. The urge being constantly to move upwardly toward the light, the flies are thus guided to the opposite or outside of the screen.

Having thus described my invention, what I claim is:—

- 20 1. A device of the character described comprising an inverted substantially V-shaped frame including a pair of converging strips forming the sides thereof, wire mesh fabric sections secured to the edges 25 of the frame, a cross slat of less width than the frame and having an inwardly beveled edge secured in said frame at a point near the lower end thereof and in connection with the wire mesh fabric sections, forming an 30 enclosure having an opening in the lower portion thereof, said cross slat being provided with a channel forming a bait recep-

tacle, an exit spout for said enclosure and means provided on one of the sides of the frame, in proximity to one end of said bait 35 receptacle and above the channel therein whereby access may be had to the latter.

2. A device of the character described comprising an inverted substantially V-shaped enclosure having a foraminous front 40 and rear wall, an exit spout extending through said rear wall near the apex thereof and further projecting outwardly and upwardly therefrom, a pair of oppositely disposed perforated leg members carried by the 45 spout and positioned against the inner face of said rear wall and secured to the side portions of the enclosure, and an upwardly extending perforated ear carried by the spout and adapted to be secured to the apex 50 of the enclosure.

3. A device for the purpose set forth comprising an enclosure forming body including a pair of converging side walls, a foraminous front wall and a foraminous rear 55 wall, an opaque triangular shaped shade element secured against the outer face of the front wall at the top thereof, and an exit spout extending through the upper portion of the rear wall and having its inner end 60 opposing said element.

In testimony whereof, I affix my signature hereto.

JEREMIAH MARSDEN
